Primary Examiner — Jonathan J Han

(57) **CLAIM**

I claim the ornamental design for a shoe, as shown and described.

DESCRIPTION

FIG. 1 is a perspective view of a shoe in accordance with an embodiment of the design;

FIG. 2 is a right side view of the shoe of FIG. 1;

FIG. 3 is a left side view of the shoe of FIG. 1;

FIG. 4 is a front view of the shoe of FIG. 1;

FIG. 5 is a rear view of the shoe of FIG. 1;

FIG. 6 is a top view of the shoe of FIG. 1; and,

FIG. 7 is a bottom view of the shoe of FIG. 1.

The dash-dash broken lines are for the purpose of illustrating portions of the shoe that form no part of the claimed design.
